CLAIM

The ornamental design for a cutting tool, as shown and described.

DESCRIPTION

FIG. 1 is a perspective view of a cutting tool showing our new design;

FIG. 2 is a right side elevational view showing the design for the cutting tool of FIG. 1;

FIG. 3 is a left side elevational view showing the design for the cutting tool of FIG. 1;

FIG. 4 is a front elevational view showing the design for the cutting tool of FIG. 1;

FIG. 5 is a rear elevational view showing the design for the cutting tool of FIG. 1;

FIG. 6 is a top plan view showing the design for the cutting tool of FIG. 1; and,

FIG. 7 is a bottom plan view showing the design for the cutting tool of FIG. 1.

The broken lines shown in the drawings illustrate portions of the cutting tool that form no part of the claimed design.
